CLAIM

The ornamental design for a log splitter as shown and described.

DESCRIPTION

FIG. 1 is a front perspective view of a log splitter
FIG. 2 is a right side view thereof;
FIG. 3 is a left side view thereof;
FIG. 4 is a rear view thereof;
FIG. 5 is a front view thereof;
FIG. 6 is a top view thereof;
FIG. 7 is a top view thereof; and,
FIG. 8 is a front perspective view of a log splitter in an alternate position.
The broken lines in the drawings illustrate portions of the log splitter, and form no part of the claimed design.

1 Claim, 8 Drawing Sheets
